UNITED STATES PATENT OFFICE

156,839

TABLECLOTH OR THE LIKE

Frederick Pilitz, West Hempstead, N. Y.

Application July 15, 1948, Serial No. 147,581

Term of patent 3½ years

(Cl. D92—26)

To all whom it may concern:

Be it known that I, Frederick Pilitz, a citizen of the United States, residing at West Hempstead, county of Nassau and State of New York, have invented a new, original, and ornamental Design for a Tablecloth or the like, of which the following is a specification, reference being had to the accompanying drawing, forming a part thereof.

The figure is a face view of a tablecloth or the like, showing my new design.

I claim:

The ornamental design for a tablecloth or the like, as shown.

FREDERICK PILITZ.
